W. H. H. BABBITT, OF NEW CORNER, INDIANA.

Letters Patent No. 83,017, dated October 13, 1868.

IMPROVEMENT IN GAITER-BOOTS.

The Schedule referred to in these Letters Patent and making part of the same.

To all whom it may concern:

Be it known that I, W. H. H. BABBITT, of New Corner, in the county of Delaware, and State of Indiana, have invented a new and useful Improvement in Gaiter-Boots; and I do hereby declare that the following is a full, clear, and exact description thereof, which will enable those skilled in the art to make and use the same, reference being had to the accompanying drawings, forming part of this specification.

This invention relates to an improvement in gaiter-boots, and is confined to the fastening of the gaiter around the ankle, and to the parts connected therewith, whereby the fastening is rendered durable, and the ankle is properly supported.

The invention consists in attaching to the edges of the leg of the gaiter, (or to what may be called the latches where the lacing is usually applied,) metallic plates, which hook together and securely fasten the leg of the gaiter around and above the ankle, thereby affording support to weak ankles, and preserving those that are not weak in a healthy condition.

The drawing represents a perspective view of a gaiter constructed according to my invention.

A is a plate, of any suitable metal, (as brass or copper,) which is attached to one of the edges of the leg (or latches) by rivets or otherwise, as seen in the drawing.

The edge of this plate is turned outward, so as to form a hook its whole length, or a portion of its length. It is placed between the outer leather of the leg B and the lining C, the size and form of the plate being indicated by dotted lines.

Attached to the other edge of the leg or latchet by a folding leather, D, there is another plate, E, of the same material, in which there is a long slot, which

corresponds in length with the hook A, and which is sufficiently broad to admit the hook, and allow it to clasp around its outer edge, f, when the gaiter is fastened.

The folding leather D is sewed tightly to each latchet of the gaiter, and also below the lower ends of the plates. When the gaiter is fastened around the ankle, the folding leather D is doubled over the ankle.

G is the flap, or back latchet, which is attached at its lower end, and swings back, and allows the leather, D, to expand when the foot is admitted into the gaiter, as seen in the drawing.

It will be seen that by this method of forming and fastening the gaiter, no shirred or elastic cloth or material is necessary, that eyelets and lacings are dispensed with, and that the leg of the gaiter is as impervious to water as its foot.

To those who are troubled with weak ankles, this gaiter furnishes a sure means of support, as the rigidity of the fastening prevents the ankle from turning or being sprained in treading on stones or other obstructions.

I claim as new, and desire to secure by Letters Patent—

1. In combination with a gaiter, the plates A and E, and the folding leather D, arranged substantially as described, for the purposes set forth.

2. The flap G, in combination with the plates A and E, arranged and operating substantially as described, for the purposes set forth.

W. H. H. BABBITT.
